FLUID CIRCULATING DEVICE

Harry E. Cullen and Henry O. Ronning, Minneapolis, Minn., assignors to Henry P. Watson, Minneapolis, Minn.; Alfred F. Pillsbury and Bessie Watson executors of said Henry P. Watson, deceased

Application November 4, 1931, Serial No. 572,970

6 Claims. (Cl. 62—126)

This invention relates generally to improvements in fluid circulating devices and particularly to the application of such devices to drinking water coolers and has, among its objects: to provide means whereby refrigerating contact with a given surface area of a vessel may be had substantially throughout the entire area to associate a pair of tubular elements in such a way as to provide a fluid circulating passage in which substantially the entire area of the inner surface of each element is opposed to the surface of the other; to provide a spiral circulating passage by the use of a sleeve which has certain portions spaced from the wall of the receptacle and which has other portions having only a spiral line contact with the receptacle; to provide, by the use of a sleeve, a spiral fluid circulating passage which repeatedly circumscribes a vessel, and in which one wall is formed by the vessel, whereby refrigerating fluid may be caused to contact the wall of the vessel substantially throughout the entire area covered by the sleeve; and generally to provide a device of the kind described which can be very cheaply manufactured and which can be easily assembled.

Features of the invention include all the details of construction, along with the broader ideas of means inherent in the disclosure.

Objects, features and advantages of the invention will be set forth in the description of the drawings forming a part of this application, and in said drawings

Figure 1 is a vertical section through a water cooling apparatus, showing one embodiment of this invention;

Figure 2 is a detail section of a drinking water receptacle showing the application of the invention thereto; and

Figure 3 is a plan section on line 3—3 of Figure 1.

The water receptacle is indicated at 1 and is arranged within a chamber 2 at the top of the main casing generally indicated by the numeral 3. The water receptacle is spaced from the wall of the chamber and suitable insulating sheathing, not shown, is usually wrapped or packed about it.

The vessel 1 is downwardly tapered. A conical sleeve 6 is fitted over the outer side of the vessel and its general angle of taper corresponds to that of the vessel. The sleeve is punched to provide portions 7 which are spaced from the wall of the vessel 1 and these portions are connected by portions 8 which converge downwardly and which at their angular junctions with the portions 7 have a sealing spiral line or knife-edge contact as

at 9. By this means, a single continuous spiral passage generally indicated at 10 is provided. As the sleeve is forced into position, the spiral line contact is obtained. Afterwards, the sleeve is circumferentially soldered to vessel 1 at opposite ends as at 13—14. The portions 8 allow for expansion and contraction of the sleeve lengthwise as well as circumferentially without putting undue strain on the soldered connections 13—14.

The spiral passage feature is broader than its application to the drinking water dispensing field. The gist of the invention is the provision of conductive contact throughout substantially the entire surface area of the conduction zone. The idea can be applied to piping, wherein two tubular elements are so associated (and either one or both formed) as to provide a spiral passage, whereby any suitable fluid can be made to contact substantially the entire areas of the opposed surfaces of the elements. Either one or both of the elements may be shaped. It is preferable, however, to shape one of them to provide the spiral partitioning portion which has a continuous spiral sealing line contact, with the wall of the other element. The use of refrigeration coils is common, but with coils the conductive contact is only a spiral tangent line contact. In the present device, the conduction zone is not defined by a line contact, but by maximum surface contact, just the reverse of that of the tangent contact of the ordinary spiral tube.

Vessels having hollow walls are also used, but with these devices there is no cheap and sure way that conductive contact over the entire surface can be assured, since fluid follows the path of least resistance, or "short cuts" from point of entry to point of exit. The spiral passage of this invention prevents short cutting and the fluid is forced to contact the entire area of the surfaces of the conducting walls. It is noted that in the present embodiment, there is only a single passage and its conductive wall includes substantially the entire area of that portion of the receptacle (or one tubular element) which is covered by or opposed to the sleeve (or other tubular element) and this single passage is repeatedly circumscribing.

The tapering of the vessel and sleeve facilitates assembly, as well as the production and maintenance of the spiral line contact. Moreover, the screw thread-like formation of the sleeve permits of expansion and contraction due to changes in temperature, without due strain on the soldered or brazed connections used to secure the ends of the sleeve to the receptacle. It is to be noted that

the bottom of the receptacle is not covered by the sleeve.

The use of the sleeve in the manner disclosed is also advantageous because its length can be varied according to the amount of refrigerating effect desired, and its use assures a contact of the refrigerant substantially over the entire surface of the outer or inner wall of the vessel with which it may be associated. Due to the tapered construction, the sleeve can be forced firmly into position in a manner to obtain an unbroken seal ing contact along the spiral line 9.

It is entirely objectionable to place refrigerating coils in direct contact with drinking water because of the danger of contamination. The problem has been to obtain a large surface contact of the refrigerant without the use of the coils and insofar as we are aware, this problem has never before been satisfactorily solved. Such devices as are commercially known, are expensive to manufacture and have a minimum of refrigerant efficiency.

The sleeve is formed by pressing, and can be made of any suitable metal, such as steel, but preferably both receptacle and sleeve are made of pure nickel. The sleeve may be formed by placing it over a spiral mandrel and then pressing to give it a spiral shape.

Openings 16-17 are provided in the sleeve at opposite ends of the spiral passage, as shown at the left of Figure 2, and interiorly threaded tubular elements 18 and 19 are secured as shown. The refrigerating apparatus which is associated with the structure of this invention is of the low pressure control type designed for the use of sulphur dioxide as a refrigerant. The apparatus per se is not claimed, except generally as means in combination, to produce refrigerating effects in the spiral passage.

The expansion valve is generally indicated at 20, and this valve is suitably connected by nipple 21 with element 19 communicating with the lower extremity of the spiral passage. A nipple 22 is in threaded connection with the element 18 at the upper end of the spiral passage. The connection of these elements with the refrigerating apparatus is described below.

In the bottom of the receptacle 1 there is formed an opening 25, and with this opening is associated an elbow 26 and pipe 27 forming a passage for withdrawing water. The pipe 27 passes through an opening 28 in the insulating wall 29 of the upper chamber 2 and is terminally threaded. To this threaded portion is attached a spigot 32 of any suitable construction, only a fragment of the spigot casing being shown. A washer 33 is interposed, as shown, between the end of the casing and the plate or sheet 34 of the main housing 3.

Provision is made for the control of the compressor motor by a thermostat, the bulb of which is indicated at 40. This thermostat is detachably mounted in the lower wall of the receptacle 1. The bulb passes upwardly through a pipe 42 which pipe has threaded connection with a plug 43 passing through opening 44 of the vessel 1. The end of the pipe 42 compresses packing 46 in the plug and surrounding the bulb 40. Gaskets 47-48 are interposed as shown, and nut 50 sealingly clamps the plug in operative position. The thermostat is of the gas expansion type and the bulb has the usual tube 52 which extends downwardly through a plug 53. The pipe passes to a switch control box 54; see Figure 1. Inasmuch as the present invention does not relate to the construction of this thermostatically controlled

mechanism, the construction is not illustrated. However, the wiring connection for the motor is carried through cable 55. The motor is indicated at 56. The bulb usually controls a switch in the motor circuit.

Referring to Figure 1, the upper compartment 2 has a removable cover which also forms a cover for the water receptacle, and which is of the double-walled construction to reduce heat conduction to the compartment 2. This cover is generally indicated at 60. The walls 61-62 of the compartment act to clampingly secure a gasket 63 in operative position. The water bottle is indicated at 64 and the neck end of the bottle is sealingly engaged with the gasket and extends through the gasket into the water receptacle in the usual manner.

The refrigerating plant or machinery is arranged within the casing 3 below the compartment 2 and includes the usual compressor generally indicated at 70 operated by means of a pulley 71, the pulley having fans 72-73 respectively on its opposite faces. The refrigeration machinery is mounted on a frame generally indicated at 74, the compressor on the upper side of the frame and the motor 56 on the lower side. This frame 74 is suspended by cushion members one of which is indicated at 75.

The condenser coils are indicated at 80 and lie between the pulley fan and a louver indicated at 81. A second louver 82 is provided on the opposite side of the housing 3. The condenser coil is connected by one end with the pressure side of the pump at 83 and the opposite end of the coil is connected to the receiver 84 as at 85. The receiver is connected by pipe 86 with the expansion valve 20. The receiver is also suspended from the lower side of the frame 74. The suction side of the compressor is connected by pipe 87 with the nipple 22. The motor operates the pulley 40 through belt 88. The motor is mounted on a plate 89 adjustable on screws 90 which are attached to a plate 100 carried by frame 74.

It is to be noted that the portions 7 which are spaced from the receptacle are substantially parallel with the axes of the receptacle and sleeve, and it will be further noted that they are substantially elongated in this axial direction. This is a valuable feature because by constructing the sleeve in this manner (or the receptacle or both sleeve and receptacle) the length of the spiral line contact is substantially reduced, and increased flexibility of the wall of the sleeve in direction of introduction or assembly is obtained, and thus a substantially perfect spiral line sealing contact between the tubular members is unfailingly obtained.

It will be noted that the cross-sectional area of the spiral space is elongated in direction of the axis of the sleeve and receptacle and it will also be noted that these spaces are narrow in a direction transverse to the axis. This obtains more refrigerating efficiency. It is further noted that the sleeve can be die-stamped and this is of considerable economic importance.

We claim as our invention:

1. In a device of the class described, a tapered receptacle, a tapered sleeve fitting over the outside of the receptacle and having portions of its wall spaced from the wall of the receptacle and having other portions having a continuous spiral line contact with the receptacle, to provide a spiral fluid circulating passage one wall of which is formed by the receptacle, those portions of the sleeve which are spaced from the receptacle wall

being substantially parallel with the axes of the receptacle and sleeve.

2. In a water dispensing apparatus, a receptacle, means for withdrawing water from the bottom of the receptacle, means cooperative with the outer surface of the vessel to provide a fluid circulating passage, means for producing refrigerant effects in the passage, thermostatic means for controlling said last mentioned means including a bulb traversing the lower wall of the receptacle, and means by which the said bulb is detachably secured in operative position in the receptacle wall.

3. A device of the class described comprising a vessel of substantially conical configuration open at the top and tapering downwardly, and having means at the bottom for draining its contents, a tapered sleeve surrounding the vessel and having its walls formed to cooperate with the wall of the receptacle to provide a spiral fluid circulating passage in which substantially the entire area of the inner surface of each element is exposed to the other, and means for circulating refrigerant fluid through the passage, the cross-sectional area of the spiral chamber being substantially elongated in direction axially of the vessel and sleeve to reduce the length of the spiral line of contact, whereby the tapering of both elements and the reduction in length of the spiral contact facilitates intimate contact and the maintenance of said contact to form a perfect seal.

4. A pair of tapered tubular elements one surrounding the other, one of the elements having portions of its wall spaced from the other and having other portions having a spiral line contact

with the other, the spaced portions of the surrounding element being substantially parallel with the axes of the tubular elements.

5. In a water dispensing apparatus a tapered water dispensing receptacle and means for controlling the dispensing of water therefrom, a tapered tubular element surrounding the receptacle, said receptacle and element being formed to cooperate to provide a spiral fluid circulating passage in which substantially the entire area of the inner surfaces of each element are exposed to the surface of the other, the passage so formed being elongated in direction of the axis of the receptacle and relatively narrow in a direction transverse to said axis and being tapered from below upwardly, and means for circulating a refrigerant fluid through the passage.

6. A drinking water cooling and dispensing apparatus, comprising a smooth walled water receptacle of tapered configuration open at the top, means by which the top can be closed by the neck of an inverted bottle, a tapered sleeve surrounding the water receptacle at the outer side and having a portion of its wall spaced from the smooth wall of the receptacle, and having other portions having a sealing spiral line contact with the receptacle all to provide a spiral fluid circulating passage, means for circulating refrigerant through the spiral passage, and a passage communicating with the receptacle for controlling draw-off of the cooled water therefrom, and not passing either through the receptacle wall or the sleeve.
